UNITED STATES PATENT OFFICE.

WILLIAM L. BARRON, OF NEW YORK, N. Y., ASSIGNOR TO THE SINGER MANUFACTURING COMPANY, A CORPORATION OF NEW JERSEY.

WORK-HOLDER FOR SEWING-MACHINES.

1,151,535.

Specification of Letters Patent. Patented Aug. 24, 1915.

Application filed April 12, 1912. Serial No. 690,413.

To all whom it may concern:

Be it known that I, WILLIAM L. BARRON, a citizen of the United States, residing at New York, in the county of New York and State of New York, have invented certain new and useful Improvements in Work-Holders for Sewing-Machines, of which the following is a specification, reference being had therein to the accompanying drawings.

10 This invention relates to an improvement in work-holders for sewing machines more particularly of that class in which feeding and lateral jogging movements are produced between the stitch-forming mechanism and the work-holder whereby groups of distributed tacking stitches of predetermined number are applied to the work; and it is designed more particularly for closing the ends of the pockets for the steels of corsets in 20 such manner as to insure the close proximity of the tacking stitches to the extremities of the steels without endangering the breaking of the needle by striking the latter.

In its preferred form, the work-holder is 25 constructed with a frame having a lower member to which is secured an upwardly inclined spring-blade, and an upper member in which is journaled a presser-bar having a foot provided with a needle-aperture and 30 with a depending stop-shoulder or shoulders disposed close to the needle-aperture and intermediate the same and the free extremity of said spring-blade.

The body fabric usually has upon one 35 face a strip secured thereon by spaced parallel seams forming open-ended pockets containing the steels. In the use of the attachment, the presser-foot is lifted slightly above the spring-blade, and the garment is introduced between them and drawn therebetween by the operator until the end of the portion of fabric distended by the steels encounters and is arrested by the depending shoulders of the foot, when the latter is lowered to clamp the fabric and the tacking 45 stitches are applied close to the ends of the steels.

In the accompanying drawings, Figure 1 is a rear side elevation of a Singer button-50 sewing machine constructed substantially in accordance with the United States patent to G. S. Gatchell No. 798,130, of August 29, 1905, and embodying the present improvement; and Fig. 2 a perspective view of a 55 portion of the controlling cam-wheel and

its connections with the work-holder.. Fig. 3 is a perspective view of the presser-foot taken from the upper side, Fig. 4 a similar view of the lower member of the work-holder carrying the spring-blade, and Fig. 60 5 a perspective view representing the under side of the presser-foot. Fig. 6 is an enlarged sectional elevation showing the method of introduction of the fabric for a stitching operation. Fig. 7 is a perspective 65 view of a portion of fabric showing the ends of two steels confined in their respective pockets by transverse tacking stitches.

The machine represented in the drawings is of that type comprising a rectilinearly reciprocating needle and complementary 70 stitch-forming mechanism and a laterally and longitudinally moving work-holder comprising a frame having the slide-plate 1 and overhanging bracket-arm 2 with head 3 75 in which is journaled for vertical movement the flat presser-bar 4 normally pressed downwardly by means of the spring-arm 5 sustained by the bracket-arm. To the reduced forward end of the slide-plate 1 is secured, 80 by means of the dowel-pins 6, the stud-screw 7 and nut 8, the shank 9 of the work-supporting plate 10 constituting the lower jaw of the work-holder which is shown provided with the double crescent-shaped 85 needle-aperture 11 around which its upper face is roughened or serrated at 12. The work-supporting plate 12 has secured to its outer extremity by means of rivets 13 the 90 foot 14 of an upwardly and backwardly inclined spring-blade 15 whose extremity 16 is shown disposed adjacent the forward edge of the needle-aperture 11 and is shaped to conform therewith.

The presser-bar 4 has a forwardly offset 95 lower portion 4^x which carries the presser-foot 17 having a needle-aperture 18 in register with the aperture 11 of the work-supporting plate 10 with which it corresponds in shape. The bottom of the presser-foot has a roughened or serrated surface 19 rearward of the aperture 18 in front of which it is formed with a transverse notch at 20 and provided with the depending lips 21 to afford stop-shoulders for the work in its introduction and positioning in the work-holder.

The machine in connection with which the present improvement is illustrated is constructed with the usual bed-plate 22 and 110

overhanging bracket-arm 23 in which is journaled the main-shaft 24 connected by means of the worm 25 and worm-wheel 26, represented in dotted lines in Fig. 1, to the 5 cam-wheel 27. The cam-wheel is provided in its rearward face with a feed-cam groove 28 entered by a stud 29 upon the upper end of the lever 30 mounted upon the fixed fulcrum 31 and having upon its lower end a ball-and-socket connection 32 with the link member 33 connected at the opposite end by means of the swivel-block 34 with one arm 35 of an angle-lever whose other arm 36 is connected with a cross slide-block 37 10 to which the work-holder slide-plate 1 is suitably attached. The cam-groove 28 is formed in a series of steps to impart through the mechanism just described transverse to-and-fro feeding movements to the work-holder relative to the stitch-forming mechanism.

The slide-plate 1 has at its rear end the rigid pin or post 38 embraced by the tubular depending arm 39 of a lever fulcrumed upon 25 the bracket 40 and having an upper arm 41 carrying the roller-stud 42 which enters the jogging cam-groove 43 of the cam-wheel 27. The post 38 has adjustably secured thereon by means of the set-screw 44 the block 45 30 fitted within the bore of the arm 39 and adapted to communicate reciprocatory or jogging movements therefrom to the slide-plate 1 through the post 38.

The stitch-forming mechanism comprises 35 the usual needle 46 carried by the rectilinearly reciprocating needle-bar 47 journaled in the head of the bracket-arm 23 and operatively connected with the main-shaft 24.

In order to raise and lower the upper 40 member of the work-holder or clamp, the presser-bar 4 is provided with a forwardly extending pin 48 passing through a slot in the cover-plate of the head 3 of the work-holder bracket-arm, and beneath this pin extends the laterally projecting arm 49 having a boss 50 adjustably secured by means of the set-screw 51 upon the lower end of the lifting bar 52 which is journaled in the head of the bracket-arm 23 and provided near its 45 upper end with the fixed collar 53 beneath which extends the forward extremity of the rock-lever 54 mounted upon the fixed fulcrum-stud 55 and adapted to be actuated by a treadle connection to lift the bar 52 for 50 raising the upper clamp member. The lower extremity of the head of the bracket-arm 23 affords a stop-shoulder 23^x for engagement of the upper end of the boss 50 of the lateral arm 49, and in practice this is 55 so set upon the lifting bar 52 that when the foot 17 is raised by actuation of the rock-lever 54, the lower operative face 19 of the foot will be only slightly above the free operative end of the spring-blade 15, as represented in Fig. 6, so as to permit the body

fabric to pass freely between such parts while the thickened portion thereof containing the ends of the corset steels will be engaged by the stop-shoulders 21 in the introduction of the garment for a stitching operation.

As represented in Fig. 7, the body fabric *a* has secured to its inner face by means of the parallel lines *s* of straight-away stitching the pocket strip *b* with inturned edges and interposed lining strip *c*, thereby producing the initially open-ended pockets *d* in which are confined the steels *e*, in practice covered with paper or other suitable material and provided with the metal tips *e'*. As 80 before indicated, preparatory to a stitching operation the presser-foot is lifted to clear the free end of the spring-blade 15 and the garment drawn in between them until the thickened and stiffened portions adjacent 85 the ends of the steels *e* are engaged by the depending stop-shoulders 21, the adjacent unstiffened portion of the fabric being deflected below the latter, as represented in Fig. 6. The presser-foot is then lowered 90 and the machine set in motion, which, in the machine represented in the drawings, causes the application of two superposed crescent-shaped transverse seams *t* across both pockets *d* close to the tips *e'*. The foot 17 95 is formed at its forward edge with an angular projection 17^x serving as a pointer in connection with the middle seam *s* to gage the position of the tacking cross-seams *t*.

It will be observed that the notch 20 in 100 the bottom of the presser-foot affords work-engaging faces at different levels upon opposite sides of the needle-aperture 11 so as to properly accommodate the thicker and thinner portions of the fabric, that portion 105 provided with the steels *e* being maintained seated within the bearing face of said notch by the resiliently sustained work-supporting member afforded by the free outer end of the spring-blade 15. While the stop-shoulder 110 or shoulders 21 are preferably disposed intermediate the needle-aperture and the adjacent extremity of the spring-blade 15 to adapt the work-holder for closing the pockets for the steels in corsets, it is evident 115 that the stops may be otherwise located relative to the needle-aperture for different classes of work, and also that the resilient work-support need not be confined wholly to a position at one side of the needle-aperture, so long as it operates, when the presser-foot is lifted, to lightly press the work against the bottom of the presser-foot for engagement with the depending shoulder so as to insure the proper location of the thickened part of the fabric designed to receive 120 the tacking stitches.

It is not essential, in the broader aspect of the present improvement, that the spring-blade or pressure-member be sustained by 125

the lower work-clamping member, nor that the work-positioning stop-shoulder be located upon the upper work-clamping member, as the nature of the work to be performed and the character of the garment operated upon may exercise an influence in determining in reference to these details.

Having thus set forth the nature of the invention, what I claim herein is:—

10 1. A sewing machine work-holder comprising a clamping foot provided with two work-engaging faces and with a needle aperture intermediate said faces, a resilient work-supporting member opposed to one of said faces, and a stop shoulder intermediate the end of said work-supporting member and the needle aperture.

2. A sewing machine work-holder comprising a clamping foot having its bottom 20 notched to afford work-engaging faces at different levels and provided with a needle-aperture intermediate said faces and with adjacent depending stop-shoulders, and a work-supporting spring-blade having a free 25 outer end opposed to the notched portion of said presser-foot.

3. A sewing machine work-holder comprising a clamping foot provided with a needle-aperture intermediate work-engaging 30 faces in different planes, a stop-shoulder intermediate said needle-aperture and one of the said work-engaging faces, and an upwardly inclined work-supporting member adapted to coöperate with one of the work-engaging faces of said foot.

4. A sewing machine work-holder comprising a frame, a spring-blade secured to and sustained by said frame, and a presser-bar journaled in said frame and having a 40 foot provided with a needle-aperture and with a depending stop-shoulder intermediate said needle-aperture and the operative edge of said spring-blade.

5. A sewing machine work-holder comprising a frame, a work-supporting plate secured thereto and provided with a needle-aperture, an upwardly inclined spring-blade secured to said work-supporting plate and having its free edge adjacent said needle-aperture, and a spring-pressed presser-bar 50 journaled in said frame and having a foot provided with a needle-aperture in register with that of the work-supporting plate and provided also with a depending stop-shoulder disposed intermediate said needle-aperture and the adjacent edge of said spring-blade.

6. In a sewing machine, the combination 60 with stitch-forming mechanism, of a work-holder comprising a frame, a work-support-

ing plate secured thereto and provided with a needle-aperture, an upwardly inclined spring-blade secured to said work-supporting plate and having its free edge adjacent said needle-aperture, and a spring-pressed 65 presser-bar journaled in said frame and having a foot provided with a needle-aperture in register with that of the work-supporting plate and provided also with a depending stop-shoulder adjacent said needle-aperture, 70 and presser-foot lifting means including a stop whereby the rise of the presser-foot is arrested with its lower face at substantially the level of the outer operative portion of said spring-blade. 75

7. A sewing machine work-holder comprising a clamping foot provided with a needle-aperture intermediate work-engaging faces in different planes, a stop-shoulder intermediate said needle-aperture and one 80 of the said work-engaging faces, and a resilient work-supporting member adapted to co-operate with one of the work-engaging faces of said foot.

8. A sewing machine work-holder comprising a spring-pressed clamping foot formed with a needle-aperture and with a notch extending to the outer edge of said foot, a stop-shoulder intermediate said needle-aperture and notch, and a resilient work-supporting member adapted to coöperate with said notched portion of the clamping foot in arresting a projection from the body of a fabric. 85

9. In a sewing machine, the combination 95 with stitch-forming mechanism, of a work-holder comprising opposed upper and lower clamping members relatively movable toward and from each other, an intermediate spring-member adapted to press the work 100 upon the face of one of said clamping members in their retracted relation, and a stop-shoulder extending partially across the space between the last-named clamping member and said spring-member and adapted 105 to engage and arrest a projection from the body of a fabric introduced between them, and lifting means including a stop whereby the retraction of the last-named clamping member is arrested when its lower 110 face is at substantially the level of said spring-member.

In testimony whereof, I have signed my name to this specification, in the presence of two subscribing witnesses.

WILLIAM L. BARRON.
